(57) **CLAIM**

The ornamental design for a watch dial, as shown and described.

DESCRIPTION

FIG. 1 is a front view of the watch components according to a first embodiment of my design;

FIG. 2 is a front perspective view thereof;

FIG. 3 is a front view of the watch components according to a second embodiment of my design; and,

FIG. 4 is a front perspective view thereof.

The month is displayed using the twelve rectangular apertures around the circumference of the dial.

FIG. 4

UNITED STATES PATENT AND TRADEMARK OFFICE
CERTIFICATE OF CORRECTION

PATENT NO. : D718,648 S
APPLICATION NO. : 29/415068
DATED : December 2, 2014
INVENTOR(S) : Marla Cristina Calvani

Page 1 of 3

It is certified that error appears in the above-identified patent and that said Letters Patent is hereby corrected as shown below:

On the title page,

Delete Title page with illustrative Figure, and replace with new Title page with illustrative Figure. (attached)

Column 1, item (30), correct the Foreign Application Priority Data section as follows:

Delete “1383/87” and add --138387--.

In the drawings,

Delete Drawing Sheet 4, and replace with new Drawing Sheet 4. (attached)

Signed and Sealed this
Third Day of May, 2016

Michelle K. Lee
Director of the United States Patent and Trademark Office
